CHIN STRAP BUCKLE

Max Kiessling, Waterbury, Conn., assignor to The American Fastener Company, Waterbury, Conn., a corporation of Connecticut

Application March 13, 1943, Serial No. 479,001

5 Claims. (Cl. 24—170)

This invention relates to buckles and more particularly to a chin strap buckle for use on a military helmet for detachably and adjustably locking the free end of the chin strap to the buckle member to which the fixed end of the chin strap has previously been riveted.

One object of the present invention is to provide an improved chin strap buckle of the above nature in which the free end of the chin strap is releasably locked or clinched by friction in an open slot of the buckle member by means of a swinging cam lever or crossbar.

Another object is to provide a device of the above nature which will be simple in construction, inexpensive to manufacture, easy to install and manipulate; compact, ornamental in appearance and very efficient and durable in use.

With these and other objects in view, there has been illustrated on the accompanying drawings one form in which the invention may conveniently be embodied in practice.

In the drawings:

Figure 1 represents a longitudinal sectional view of the improved buckle as it appears when installed upon a chin strap.

Figure 2 is a top plan view of the same with parts broken away to illustrate the interior construction.

Figure 3 is a perspective view of the frame of the chin strap buckle, shown separately.

Figure 4 is a perspective view of a modified form of cam lever.

Figure 5 is a longitudinal sectional view, similar to Figure 1, of a modified form of buckle in which the open slot is depressed to provide a smooth grip of greater contact upon the free end of the strap.

Figure 6 is a sectional view, similar to Figures 1 and 5, of another modified form of buckle in which the edges of the open slot are raised to provide upstanding teeth for more securely gripping the free end of the strap.

In the manufacture of chin straps for helmets it has been found that the leather of such straps usually varies in thickness considerably. With the present types of chin strap buckles, an excessively thin strap was likely to slip in the buckle, whereas an excessively thick one would be cut or scratched by the buckle cam lever.

By means of the present invention the above and other disadvantages have been avoided.

Referring now to the drawings in which like reference numerals denote corresponding parts throughout the several views the numeral 10 indicates the frame of the buckle which is made

preferably rectangular in plan view, and is provided with a pair of upstanding parallel triangular side flanges 11 and 12, which are curved at their rear upper ends and provided with a pair of circular aligned pivot holes 12a, 13a, respectively.

The buckle frame 10 is provided with a flat base 13 having a circular aperture 14 in its forward portion for receiving a rivet 15, which when headed over (as shown in Figure 1) serves to hold the fixed end 16 of a chin strap of leather, rubber, fabric or the like rigidly in position upon the top of the base 13.

In order to hold the loose or free end 17 of the chin strap in the adjusted releasable position shown in Figures 1 and 2, and overlying base 13 the fixed end 16 of said chin strap, provision is made of an elongated cross slot 18 located in the base 13 of the buckle frame 10 below the position of the pivot holes 12a, 13a. Provision is also made of a hinge cam lever or cross bar 19 comprising an elongated intermediate straight section 20 terminating at its forward end in an upwardly-extending curved extremity 21, which 25 serves as a handle to permit the cam lever to be readily raised from the locked position shown in full lines in Figure 1 and swung to the released position shown in dotted lines in said figure. This releasing action is accomplished by the operation of inserting one finger of the user's hand beneath the curved extremity 21 and raising the cam lever 19 upwardly in a counterclockwise direction. The cam lever 19 is provided at its rear end with a downwardly and forwardly curved resilient ear section 22 which has an upstanding extremity 23 spaced a short distance from the upper straight section 20 of said cam lever. The cam lever 19 is also provided with a pair of laterally extending flat hinge pins 24 and 25 which 30 are herein shown as rectangular in cross section.

Operation.

In the use of the buckle of the present invention, the fixed end 16 of the chin strap will first be riveted upon the bottom of the base 13 of the buckle body (as shown in Figure 1). The free end 17 of said strap will then be brought around under the buckle frame and threaded forwardly through said frame while holding the tongue in 45 the open position shown by dotted lines in said figure. To lock the strap in the desired adjusted position the cam lever 19 will then be swung downwardly to the full line position, causing the bight or loop portion 26 on said strap to be engaged and pushed downwardly by the resilient

curled ear 22 of the cam lever 19 into the slot 18 formed in the base 13 at the rear of the buckle frame 10.

The bight 26 of the chin strap will thus be pressed against the sides of the slot 18 with a frictional locking action, thus clinching the strap and preventing it from slipping. It will be understood that by reason of the resiliency of the curled ear 22, the material of the strap, even if excessively thick will be prevented from becoming cut, scratched, or otherwise injured.

Modified forms

In the modified form of the cam lever 19A shown in Figure 4, provision is made of a resilient ear 27 of V-shape in cross section which serves to strengthen said ear and increase the gripping effect upon the chin strap engaged thereby.

In the modified form of the invention shown in Figure 5, the open slot 18a of the buckle frame 10a is provided with depressed edges 28 and 29 which serve to strengthen the buckle and also provide a smooth grip of greater contact upon the bight 26a of the free end 17a of the chin strap engaged thereby.

In the modified form of the invention illustrated in Figure 6, raised edges 30 and 31 are formed on the slot 18b. This construction produces a pair of parallel upstanding teeth 32 and 33 which serve to grip the free end of the chin strap very securely when the cam lever is in closed position.

While the present invention has been illustrated by means of a buckle for holding chin straps, it will be understood that it is not limited to such use, but may also be employed on suspenders, garters, wrist bands, etc., within the general spirit and scope of the present invention.

While there has been disclosed in this specification one form in which the invention may be embodied it is to be understood that this form is shown for the purpose of illustration only and that the invention is not to be limited to a specific disclosure but may be modified and embodied in various other forms without departing from its spirit. In short, the invention includes all the modifications and embodiments coming within the scope of the following claims.

Having thus fully described the invention what is claimed as new and for which it is desired to secure Letters Patent is:

1. In a buckle, a substantially rectangular frame having a flat base, a pair of apertured side flanges upstanding from said base, and a cam lever having a forwardly extending straight handle section and a downwardly, forwardly, and upwardly curled rear resilient section, said cam

lever having a pair of lateral hinge pins located above the position of said curled rear section for pivotally fitting in the apertures of said side flanges, said base having a rear cross slot located between said flanges, into which the free end of a flexible chin strap may be adjustably and resiliently clinched by said curled section when said handle is swung down against said base, the upwardly curled resilient section of said lever 10 entirely covering said slot and terminating at a point spaced from the undersurface of said handle section.

2. In a buckle, a frame having a flat base, a pair of apertured side flanges upstanding from said base, and a cam lever having a handle section adapted to press upon the fixed end of a flexible strap secured to said base, said lever having a downwardly, forwardly, and upwardly curled resilient rear section, said cam lever having a pair of lateral hinge pins adjacent said curled rear section and mounted to pivot in the apertures of said flanges, said base having a rear cross slot located between said apertures and cooperating with said curled section to clinch the strap therebetween when said handle is swung down against said base, the upwardly curled resilient section of said lever entirely covering said slot and terminating at a point spaced from the undersurface of said handle section.

3. In a buckle, a frame having a flat base, a pair of apertured side flanges upstanding from said base, and a cam lever having a forwardly extending upper handle section, said lever having a downwardly, forwardly, and upwardly extending V-shaped resilient rear section, said cam lever also having a pair of lateral rear hinge pins located above said resilient section and pivotally mounted in the apertures of said side flanges, said base having a rear cross slot located between said flanges and cooperating with the V-shaped section of said lever to clinch a strap therebetween when said handle is swung down against said base, said V-shaped section covering the full width of said slot and terminating at a point spaced from the undersurface of said handle section.

4. The buckle as defined in claim 1, in which the edges of said cross slot are depressed to provide a greater and smoother area of contact 50 on the free end of said strap by the resilient rear section of said cam lever.

5. The buckle as defined in claim 1, in which the edges of said cross slot are raised to provide teeth for causing the resilient rear section of 55 said cam lever to grip the free end of said strap more securely.

MAX KIESSLING.
